(57) **CLAIM**

The ornamental design for a brush housing, as shown, and described.

DESCRIPTION

FIG. 1 is a front view of the brush housing;

FIG. 2 is a side view of the brush housing;

FIG. 3 is a top view of the brush housing;

FIG. 4 is a bottom view of the brush housing; and,

FIG. 5 is a perspective view of the brush housing.

The broken lines depict a brush that forms no part of the claimed design. The broken away portions indicate that a specific width, length and/or height of the housing are not claimed.
